SAFETY SUPPORTING AND SUSPENSION
MEANS

Bert L. Bassett, Irvin Louis Bassett, and Willard E. Bassett, Detroit, Mich., assignors, by direct and mesne assignments to Safety-Scape Corporation, a corporation of Michigan

Application May 13, 1946, Serial No. 669,372

9 Claims. (Cl. 254—157)

1

The present invention consists in adapting an invention devised by us, pertaining to the art of fire escaping life belts and described in Letters Patent No. 1,782,951, dated November 25, 1930, for use in cleaning windows, especially of high buildings.

One of the main objects of the present invention is to provide a simple, efficient and inexpensive device, designed not only to operate as a movable fire escape, but also as a supporting means for window cleaners who perform their labors, including gaining access to windows on each floor of a building, entirely from outside a building.

Another object thereof is to provide an apparatus of compact form, conveniently supportable from a window frame of a building structure, having parts so shaped, arranged and functioning that they permit a person strapped with a life belt, to descend therefrom to the ground slowly, safely, and under circumstances that permit halting opposite any particular window or part of the building at any height.

A further object thereof is to provide improved means for suspendingly carrying an occupant of a building exteriorly thereof, in easy stays of descent to the ground, not only in case of a fire breaking out inside the building, but also for the purpose of being lowered down alongside of the building so as to come to rest at will, opposite any window it is desired to clean.

A still further object thereof is to provide, in a device of the kind described, novel mechanism operable by the person being suspendingly lowered down outside a building, for the purpose of stopping the operation of the lowering mechanism whenever he desires to do so, as well as to start it operating again.

Another object thereof is to provide, in a device of the kind described, improved means for lowering and raising flexible means attached to a person, which is flexibly mounted, for the purpose of conveying the person to the ground in safety who is leaving a burning building or room thereof, or for the purpose of conveying him outside the building to any point he desires to reach for performing labor of some kind. In this connection, two tapes are lowered and raised, to one of which the person is attached by means of a life belt, while the other tape moves up and down with the person who may pull same at will in order to start his descent from outside the building.

With the above and other objects in view, our invention consists in the combination, arrangement and details of construction disclosed in the 55

2

drawings and specification, and then more particularly pointed out in the appended claims.

In the drawings,

Wherein similar reference characters designate similar parts throughout the respective views,

Figure 1 is a side elevation of my invention partly broken away,

Figure 2 is a cross section taken through the winding and unwinding reel section of Figure 1,

Figure 3 is a top plan view of my invention, partly broken away,

Figure 4 is a fragmentary, sectional detail view of the life belt strap, and

Figure 5 is a perspective view of my invention shown mounted in position upon a window frame.

In the drawings, which are merely illustrative of our invention, we show all the parts making up the complete assembly. We will first describe the framework of the apparatus. Figure 1 shows the complete unit ready for lowering a life belt, while Figure 5 illustrates the manner of supporting this unit for proper functioning upon a building.

An open ended casing is provided, consisting of laterally spaced apart plates 10, 11, 12 and 13. A series of elongated bolts 14 are provided, which pass through all of the plates 10, 11, 12 and 13. They project snugly into a series of aligning spacer sleeves 14a, against which the plates bear frictionally. Nuts 16 screw upon the free ends of these bolts 14 and clamp the spacer sleeves 14a against said plates. The holes in the plates through which the bolts pass are designated 17.

An enclosure for the device is broadly designated 20 in Figure 5. Here is shown the correct mounting for the apparatus. In this finished construction it is seen that a lateral supporting web 21 is provided for the casing 20. In Figure 1 it is seen that it is proposed to erect the assembly of parts with the four edges of all the plates 10, 11, 12 and 13 disposed diagonally of the horizontal axis of the device so that 18, 18a designate vertically disposed corners thereof, and 19, 19a designate horizontally disposed corners thereof. At these corners the bolts 14 are positioned.

Referring to Figure 5, it is further seen that the web 21 is formed with hinge knuckles 22, 23 through which a vertical pintle 24 projects, which also has its ends projecting into the outwardly converging rigid arms 25, 26 of a strong bracket which is operatively secured to a window frame inside of a room of a building. The bracket or yoke is free to swing upon hinge leafs 31 by means of suitable hinges 29, 30 working on a trunnion 28. By such means the bracket may

readily be swung from inside the room to a point exteriorly of the building to dispose the device for immediate functioning. The window frame is designated 32.

The tackle employed for the purpose of lowering the person leaving a building by aid of the present apparatus consists of two spools or reels 33, 34, arranged alongside each other as shown in Figures 2 and 3, the opposing flanges of each of which provide an annular groove 35. Wound upon each of these reels 33, 34 are the coils of a tape 36 and 37, of strong, flexible material. These tapes are wound around two mandrels 38, 39, confined between the flanges of these spools. A drive shaft 40 is made fast to these mandrels.

We provide a governor for regulating the rotation of these reels 33, 34, not only to contribute to restraining the speed thereof but also for the purpose of stopping rotation of the reels altogether. This governor is a friction band 41 which is fixedly mounted in position suspendingly upon plate 13. A braking means is designed to move into engagement with this governor band centrifugally, and may in turn, be engaged by this band frictionally.

The governor and braking mechanism comprise a single unit. It is composed of a governor shoe-plate 42. Brake lining 43 is secured by screws or fasteners 44 upon the governor band 41. The integral lug 45 on this band 41 is hung upon a fastening screw 46 upon plate 13. The shoeplate 42 has a central hub 47 extending concentrically into the drum and has a spacer boss 48 projecting laterally of the plate 42.

A pair of oppositely arranged semi-cylindrical brake shoes 49, 50 have complementary flanges 51, 52 provided upon the hub 47. These governor brake shoes are provided with the complementary oppositely arranged slots 53, 54 and with arcuate recesses 55 which coincide with the periphery of hub 47.

The governor band 41 encloses the brake shoes 49, 50. It is a split band having the contiguously mounted straight terminals 56, 57, the slit being denoted 58. The brake shoes are held in engagement with plate 42 by means of screws 59 which project through slots 53, 54 at the outer ends thereof, and which are threaded into the plate 42. The unthreaded shanks 60 of screws 59 project directly into the slots while the heads 61 thereof abut the inner faces of brake shoes 49, 50. Shoe guide screws 62 are carried by the shoes 49, 50 which project into slots 53, 54.

At the top and bottom of the brake shoes 49, 50 are a pair of oppositely arranged pins 63. Contractile springs 64, 65 are respectively secured at opposite ends upon pins 63. They straddle the slit between shoes 49, 50. Under centrifugal action of the revolving shoes they are thrown out against the tension of the contractile springs, at which times the springs expand and the shoes crowd against the governor band 41 to restrain free rotation of the reels by means soon to be described.

Concentrically extending into the hub 47 of governor shoeplate 42 is a bushing 67 which is formed with an enlarged cylindrical flange 68 abutting the inner face of plate 13. This bushing also projects laterally of the plate 42. A shaft 69 is journaled in bushing 67, projecting clearly therethrough and having one end rotatably mounted in plate 13, and also having an enlarged disk 70 which serves to confine the governor upon shaft 69 which also abuts the flat boss on hub 47.

The disk 70 on shaft 69 abuts the plate 12, while stub 71 of shaft 69 extends rotatably into this plate.

Normally the governor band 41 is designed to be crowded tightly against brake shoes 49, 50, with enough releasable friction to stop rotation of shaft 72. This is accomplished as follows. An elongated bolt 73 projects slidably through the flat terminals 56, 57, of the governor band 41. Its head 74 bears against a short pressure spring 76 which it confines against terminal 56 of the band, by reason of the fact that this spring embraces bolt 73. The opposite end of the bolt is threaded and receives an adjustable nut 75 which bears against another pressure spring 77 embracing bolt rod 73, which spring is by this nut confined against terminal 57 of the governor band 41.

A cam is located between the opposite terminals 56, 57 of the band 41, and has the diametrically opposite lobes 79, 80 of approved shape touching these terminals. The springs 76, 77 on bolt 73 have been set so as to exert sufficient pressure to draw terminals 56, 57 toward each other a sufficient distance to crowd the band and its brake lining 43 against the two brake shoes 49, 50.

The lobes 79, 80 are formed upon a disk 78 which has a pin 81 on one side entering plate 13, and a spacer flange 82 on its other side.

Means for actuating the cam are provided. A crank member is composed of oppositely arranged parallel arms 81 and 85 connected by an intervening offset part 84. It is seen in Figure 1 that parts 84, 85 are disposed at an angle to each other. Disk 78 is made fast upon pin 81 of the cam shaft 78. A convenient bracket 86 having parallel arms 86, 86a, is mounted upon arm 85 of the bell shaped crank member by a pin 89a in such a manner that the bracket is rigidly disposed at the diagonal position shown in Figure 1. A pair of rollers 87, 88 are operatively mounted upon the opposing ends of the bracket 86.

It will also be seen from Figure 1 that we provide, directly under the bell crank bracket 84, 85, another arm 131 which at its inner end is rigidly mounted upon the rod 15 so as not to rotate thereon. At its outer end arm 131 has a pin 134 mounted therein upon which a roller 132 is journaled which has a flange 133. Arm 131 projects forwardly of the lower part of the device.

The winding up mechanism for the apparatus is as follows. An idler gear 90 on shaft 91 meshes with governor gear 72. A smaller gear 92 is arranged on shaft 91 concentrically of gear 90.

This gear 92 meshes with a relatively large gear 93 made fast on shaft 40, this being the ratchet gear which carries the central ratchet collar or band 94 made fast on enlargement 96 of shaft 40. The other cooperating ratchet collar or band 95 is supported by springs 98 in contact with ratchet band 94. The springs 98 are secured to a gear 110 hereinafter described. Ratchet band 95 is made to slide on shaft enlargement 97. Outside the case formed by plates 10, 11, 12 and 13 is a gear 100 made fast on shaft extension 99. Gear 100 meshes with gear 101 made fast on a countershaft 104 by spline 93b. A gear 109 is confined between plate 13 and a collar 103 formed on shaft 104. Shaft 104 has an enlarged extension 104a upon which at 93a gear 109 is splined, and gear 101 is also splined on this shaft extension 104a. Gear 101 is held against displacement from shaft extension 104a by a wear plate 107 which is fastened by a screw 108 to shaft 104. A bushing 105 fits into partition plate 12 and re-

ceives the stub end 106 of shaft 104. Another small bushing 102 fits in partition plate 13 in which shaft extension 104a is journaled.

Gear 109 meshes with gear 110 which is mounted upon shaft enlargement 97 of shaft 40.

Upon outside gear 100 the base flange 111 of a ferrule 113 is fastened by means of a screw 112. It is seen that shaft extension 99 has an annular groove 114 in which is tangentially positioned a pin, which is also partly seated in ferrule 113 and 10 enclosed by cap nut 116. This cap nut 116 is cap-shaped. It confines the shaft 40, while its main body is screw threaded upon the ferrule 113.

A suitable crank arm 117 is provided upon an operating crank handle 118. Arm or lever 117 is mounted upon shaft 40 for the purpose of winding the reels 33, 34.

In Figure 1 it is seen that stretch 119 of tape 36 extends down from its reel 33, tangentially of the latter, passes under roller 87 on bracket 86, 20 and over and around roller 88 at 120 so that stretch 121 of this tape hangs down from roller 88. This stretch 88 passes over roller 132 on arm 131 and then hangs down at 121. The other tape 37 hangs down also, with its stretch 121a alongside of stretch 121 of tape 36.

The stretches or ends 121a and 121 of tapes 37 and 36 may be taken, as shown in Figure 4, and attached into a suitable clevis consisting of oppositely arranged clamping jaws 122, 123, which, on their inner faces are preferably found with wavy, scalloped surfaces 124 between which are anchored, also in wavy formation, the contacting sides of the tapes 37, 36. Screws 127 are threaded into the jaws 122, 123 for clamping the tapes together nestingly. The tapes extend beyond the clevis as at 126 and are then connected to the ends of a life belt, which ends are confined in a bracing slip ring 130. The life belt 128, with its closed tight position on loop 129, is operatively attached to the tape portions 126. It is thus seen that the stretches 121, 121a of the two tapes may move in the same direction in unison with each other at the same time either up or down according as to whether the reels 33, 34, for these tapes are being wound up or paid out.

The use and operation of this apparatus is as follows. Normally the apparatus is set so as to suspend a person outside a building, around whose body and under whose shoulders the life belt 128 is operatively strapped. The apparatus, supported as shown in Figure 5, will suspend the person thus strapped onto its two tapes 36, 37, entirely upon itself, leaving the hands free to engage the side of the building for the purpose of pushing the person away from any projecting, fettering parts of the building. The weight of the body of the person thus held suspended upon this movable mount will not automatically actuate the reels to unwind same so the person may begin to descend. This is because springs 76, 77 lock the governor band 41 tightly against brake shoes 49, 50 by their tension. The person thus suspended, once he has disengaged himself from the window threshold, jacketed in the life belt 128, needs only to take hold of stretch 121 of the device and pull down on it forcibly in order to actuate the mechanism for rotating reels 33, 34.

By doing this he pushes the bell crank lever member 85 rearwardly. Arm 84 of this lever then cranks cam shaft 80 and turns the cam disk 78 effectively. This action makes the oppositely disposed lobes 79, 80, of the cam ride over terminals 56, 57, of the governor band 41 in a manner effective to push them away from each other. As

these terminals 56, 57 separate, pressure springs 76, 77 are put under tension. Separation of terminals 56, 57 of the governor band results in loosening its hold upon the brake shoes 49, 50 so that shaft 69 begins to rotate.

5 The transmission gears 90, 92, 93, 100, 101, 109, 110, because of their progressive intermeshing, begin to rotate, since shaft 40 rotates too. This permits the two reels 33, 34 to rotate at the same time in a direction to unwind tapes 36, 37. The weight of the body of the suspended person will result in the tapes moving downwardly carrying the person along with same. The brake shoes 49, 50, as soon as the reels show any slight tendency to speed up unwinding, under influence of centrifugal motion, spread out with pins or screws 62 in slots 53, 54 of governor plate and begin to crowd against the brake lining 43 of the governor band or drum 41. This exerts a desired braking effect upon the descent of the person.

As long as the suspended person keeps a tight hold upon stretch 121 of the life belt to hold it in a pulled down relation to tape 37, the reels 33, 34 will function to lower him down continuously until he reaches the ground. If the person is a window cleaner, carrying strapped to himself also his cleaning implements, he will let go of stretch 121 exactly at the time during the lowering action of his life belt 128 when he comes opposite to any particular window of the building he desires to clean. This allows springs 76, 77 to relax, causing terminals 56, 57, to forcibly approach, and turning cam lobes 79, 80 of the disk 78 to a normally registering position in a vertical plane. This releases tension on springs 76, 77 and tightens the hold of governor band 41 on the brake shoes 49, 50.

It is evident that when it is desired to reset the apparatus for another operation, it will be necessary to take hold of crank handle 117 and by means of crank 118 turn it to wind up by hand both reels together in order to wind up the coils of both tapes 36, 37 upon the reels again.

When gears 100, 110, 101 and 109 are in motion, 45 ratchet 84 remains idle and so is the governor. Springs 98 assist in rewinding the tapes so that ratchet member 95 can disengage itself from ratchet 94 as it rotates. The machine is geared three to one on rewinding the tapes to reposition them on the spools. The governor remains neutral during the rewinding operation. On descending all parts are in motion.

From the foregoing it will be seen that we have provided means enabling a person to lower himself on a suspended line from any point fixed at any elevation, whether upon a building or any other eminence, in a thoroughly safe manner, by easy stages, step by step, and also enabling him at any time desired to stop lowering himself.

60 By thus being able to be fixedly suspended in position from a point overhead, he has free use of both hands for any given purpose.

We do not confine ourselves to the exact details of construction herein set forth save as pointed 65 out in the appended claims.

What we desire to claim is:

1. In a device as described, a casing, a winding and unwinding reel therein, a human body carrying tape on said reel, a countershaft in said casing 70 having gear connections to said reel, a winding crank for said reel, a stationary governor band on said casing, a pair of oppositely arranged centrifugally controlled brake shoes engageable against said governor band to oppose the speed 75 of unreeling of said tape, an independent spring

pressing means engaging said governor band to tighten its hold against the brake shoes to prevent rotation of said reel, and manually controlled means descending with said tape for rendering said last named means inactive.

2. In a device as described, a casing, a reel mounted revolvably therein for paying out a life belt as it unwinds, a countershaft on said casing, gearing between the reel and said countershaft, a carrier fixed to the countershaft upon which oppositely movable centrifugally operable brake shoes are mounted, a stationary governor band on said casing having a pair of spaced apart terminals, means resiliently and yieldably engaging said terminals of the governor band for closing said band around the peripheral edges of said brake shoes to allow the band frictionally to stop the rotation of the reel and descent of the life belt, and means moving with said life belt graspable by the descending belt attached person for opening the governor band relatively to said brake shoes to allow the latter centrifugally to control the speed of rotation of the reel.

3. In a device as described, a casing, a pair of reels concentrically mounted therein, a pair of tapes wound upon said reels separately, a life belt carried by the lower end of one tape, a countershaft on said casing, centrifugal braking means controlling the rotation of said countershaft, gears interposed between the countershaft and the reels for imparting rotation to the gears upon rotation of said reels, a governor band with which said braking means cooperates, a guide supported from said casing having rollers over which the other tape is guided as it unwinds or winds with its reel, means yieldably tightening the engagement of said governor band and said braking means in order to stop rotation of said reel, and means actuated by pulling the last named tape for rendering said yieldable means inactive.

4. In a device as described, a casing, a pair of reels mounted rotatably therein, a pair of tapes on said reels descending and being elevated as the reels unwind and wind, the free ends of said tapes carrying a life belt, a split governor band having radially disposed contiguous terminal lugs, rotatable brake means engageable with said governor band, controlling the speed of rotation of said reels, means carried by said casing applying spring pressure to said lugs of said governor band to tighten the grip of said band against said braking means, and means controlled by pulling upon one of said tapes for rendering said governor band inactive.

5. In a device as described, a pair of adjacent reels having a pair of pendant tapes designed to be lowered and raised as said reels unwind and wind, a countershaft having gearing connected to said reels to impart rotation to said gears upon rotation of said reels, a carrier made fast on said countershaft carrying braking means for said latter shaft, means engaging said braking means for applying friction thereto to stop it from functioning, means engaging the latter means to disengage it from said braking means, and means controlled by one of said tapes controlling the actuation of said disengaging means.

6. In a device as described, a fixed governor

band having separable terminals, a life belt lowering and raising shaft, means on said shaft engaging said governor band frictionally for controlling the speed of rotation of said shaft, a cam 5 rotatably fixed so as to project between said terminals of said band, a rod passing through said lugs, springs mounted retainedly at the ends of said rod pressing said terminals against said cam and crowding said band against said means to hold the latter inoperative, said cam on being actuated rotating to separate said terminals against the tension of said springs to disengage said band from said means in order to render the first means operative, a crank for actuating said cam, and a tape moving with said life belt from said shaft, effective when pulled upon to actuate said crank.

7. In a device as described, in combination, a two-reel rotatable element, tapes raised and lowered by said reels in unison, a bearing for said element, a workable cam mounted in said bearing, a crank on said cam of a bell crank formation, a roller mounting at the free end of said crank over which one of said tapes is trained for pulling action, means rotating in time with said element for braking the rotative speed of said element, means engaging said last named means for stopping the operation thereof, and means controlled by said cam for rendering said stopping means inoperative when said tape is pulled.

8. A safety supporting and suspension means comprising a casing, a reel member rotatable in said casing, a pair of tapes about said reel member and extensible from said casing, unwinding means 35 for said reel member including a centrifugal governor, said governor including a pair of separable brake shoes, a split ring about said brake shoes engageable therewith for limiting the speed of said brake shoes and said reel member, a ring 40 expanding member on said casing, and means carried by said expanding member engageable with one of said tapes for expanding said ring upon tensioning of said one tape for permitting the increase of speed of said governor and said 45 reel member.

9. A safety supporting and suspension means comprising a winding reel, a pair of flexible members engageable about said reel, a governor operably connected to said reel for limiting the rotation thereof, a brake for said governor, and means 50 operatively engaging one of said flexible members for releasing said brake upon tensioning said one flexible member.
